ARTIFICIAL CHRISTMAS TREE BRANCH HOLDER

Albert J. Whyte, West Springfield, Mass., assignor to National Metal Specialties Co., Inc., Enfield, Conn., a corporation of Massachusetts

Filed Feb. 21, 1963, Ser. No. 260,241

4 Claims. (Cl. 248—39)

This invention is concerned with a supporting device, and particularly a device for holding elongated members, such as tree branches, out from beneath the main stem.

There has been cause to be disturbed during the Christmas season with fires to trees which are brought inside for decorative purposes during the holiday season. Attempts have been made to overcome this hazard by the introduction of artificial non-flammable trees. The artificial trees are made from various materials that do not burn. However, while overcoming the fire problem, they usually leave something to be desired because they are small in size. Others cannot be stored from year to year because they are not easily disassembled.

With these problems in mind, a stamped metal support member which lends itself both for the purpose of supporting branches of a tree on a main stem and also for being applied to members in a reverse position for making braces for a tent or other such uses, has been conceived, as will be explained hereinafter.

It is an object of the within invention to provide a strong support for holding members in a diagonal relationship to a main member.

It is an additional object of the within invention to provide a metal stamped support member for supporting objects of great weight.

It is yet a further object of the within invention to provide a metal stamped support member which may be easily fastened to a main support and easily removed therefrom.

It is still an additional object of the within invention to provide a metal stamped bifurcated support member wherein the arms are parallel to one another and wherein there are openings in the arms that are aligned with one another in parallel planes.

These and other objects are obtained by the use of a thin gauge material, preferably of metal, which is stamped into the shapes shown in the drawings. There are, in fact, two species of the generic invention disclosed, and in both instances the support member consists of a plurality of bifurcated units, each of which have an upper and lower arm extending from a central portion. All of the lower arms are radially arranged about a vertical axis at one location and all of the upper arms are radially arranged about this same vertical axis at a higher position. The upper and lower arms of each unit are provided with aligned openings for supporting a rigid member at an angle projecting from the vertical axis, and the central portions of all units are designed to fit the contour of a vertical post or member to which the units are adapted to be attached.

For a more detailed description of the invention, reference is made to the drawing, in which:

FIGURE 1 is a perspective view in front elevation of the use of the support member on a stem with a tree branch extending therefrom.

FIGURE 2 is a view of the species with the continuous ring shown in FIGURE 1, looking at the bottom thereof.

FIGURE 3 is a cross-section view taken along line 3—3 of FIGURE 2, still looking at the unit upside down.

FIGURE 4 is a view similar to FIGURE 2, of a different species of the invention, wherein the connecting member is flexible, also at the bottom.

FIGURE 5 is a view taken along line 5—5 of FIGURE 4, looking at the unit upside down.

2

FIGURE 6 is a front elevational view of the upper portion of one of the lower arms of the support shown in FIGURE 4.

The invention herein disclosed consists of two specific embodiments. The first species is disclosed in the views of FIGURES 1, 2, and 3, while the second is shown in the views of FIGURES 4, 5, and 6. The basic difference between the two embodiments is that in the species shown in FIGURES 1 through 3, there is a flat support disc or ring 8, which has mounted about its periphery a plurality of individual and separated bifurcated arms. In the species of FIGURES 4—6 there is no ring. The arms are connected to each other by a ripple fold 20, which is integral with and contiguous to the support surface 16.

15 The bifurcated arms consist of the components shown in FIGURE 3. At the end of the lower arm is the periphery, or end, of the arm 2. There is an opening 18 in this arm, which opening 18 has a recessed flange or sleeve 5. The arm 2 connects with the support contact surface 16 which is the portion connecting the arms and may be referred to as a band at an obtuse interior angle with the vertical plane. The surface of band 16 is concave so as to conform to a circular type of support member 1. Within the surface of band 16 are the openings 17 which are 20 adaptable for the passage of a wood screw 6 therethrough so as to be threaded into the support member 1. It is contemplated that the method of contact between band 16 and 1 could employ other mechanical equivalents. The bifurcated arms bend at right angles below the screw 6 25 at the inside edge of ring 8 (see FIGURE 3).

At the overlap of the disc or ring 8, it may be observed that there is an opening 9, which is rectangular and elongated, and also adapted to receive the flange or, tongue 7 of the ring 8. The flange 7 acts as a locking mechanism.

30 The actual fastening of the device consists of the locking of the flange or tongue 7 into the elongated opening 9. In the embodiment shown there is a spot weld between the ring surface and the surface of the horizontal arm segment 10. The arm segment 10 bends at 14 into segment 3, which is in a plane that is parallel to the plane of the segment 2. It can be readily seen in the view of FIGURE 3 that the openings 18 in the arms segments 3 and 2, are aligned with one another. The opening 18 in the upper portion of the arm 3 has a sleeve 4 similar to the sleeve 5. The purpose of the sleeves 5 and 4 is to prevent the cutting of the branches which are inserted into the aligned openings, and also to give greater support.

35 A plurality of the previously described bifurcated arms are placed radially about the disc 8 so that as many of these individual arms as are possible are permitted to be attached thereto. In the embodiment shown in FIGURE 2, there are five bifurcated arms. There are but five because each of the sides of the inside contacting surface 6 is almost touching the next arm on the inside of the disc 40 8. There is no further room to insert more bifurcated arms inside the center opening of the disc 8, unless the size of the radius of the disc were changed.

45 In the species shown in FIGURES 1—3, the use of the assembly of the arms as described can be seen. The various surfaces 16 are attached to the support 1, which simulates a tree trunk, and the branch 11, along with the twigs and pine needles 12 and 13 respectively, as shown in FIGURE 1, is supported by the openings 18 and their respective sleeves 4 and 5 in the parallel arms 2 and 3. The branch 11 fits within the aligned openings 11 and drops down against the support 1. It is quite simple to remove the branch assembly 11, 12, and 13, to disassemble the artificial tree. While FIGURE 1 only shows the one unit of support, namely the unit of five arms mounted on one disc 8, it is contemplated that a series of these units would 50 be spaced apart on a stem or support member 1, one above the other to simulate a tree.

In the species shown in FIGURES 4-6, the structure of the bifurcated arm assembly is similar, with the exception that instead of being mounted by a ring 8, the arms are connected to each other at the ripple fold 20, which is adjacent each side of the surface 16. The only place that the arms are not connected is at 21. There are openings 17 in the support contact band 16 which have the same configuration as the contact surfaces shown in FIGURE 3, and which are adaptable to the contour of the beam 1. The ripple fold 20 is resilient like an accordion pleat, and enables the plurality of the connected bifurcated arms to be bent around the beam 1 tightly. The use of screws 6 is contemplated to secure the various surfaces of band 16 against the beam 1. It is to be noted that all of the other components of the bifurcated arms are the same as the species of FIGURES 1-3, save for the ring 8. There is an opening 7 in the bifurcated arms of the species of FIGURES 4-6, but the opening 9 is only there because of the punch press die. Actually, the opening 9 is not necessary to the construction of this species. It is only required in the species of FIGURES 1-3, wherein the disc 8 must be locked into engagement by its flange 7.

It is also contemplated that the bifurcated arms could be used without being connected to one another. That is to say that if the fold 20 were broken off from one another, it would still be possible to screw the surfaces 16 into the beam and stagger the height around the beam 1. This might make for an even more imposing looking artificial tree, but would require more time in the assembly of the simulated tree.

It is contemplated that the within invention will lend itself to use for situations wherein it is necessary to create artificial trees, such as in the making of television shows, movies, or for the interior decoration of homes and the like, as well as for Christmas trees.

It is contemplated that the dimensions of the within invention may be changed without departing from the spirit and scope of the invention. It is also contemplated that more than five, or less than five, bifurcated arms may be used in the arrangements specified.

In consideration of the foregoing, I claim:

1. An assembly having a plurality of units, each for detachably holding a rigid member at an angle projecting from a vertical support, said units being integrally formed of substantially rigid sheet material, and each comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together.

2. An assembly having a plurality of units, each for detachably holding a rigid member at an angle projecting from a vertical support, said units being integrally formed of substantially rigid sheet material, and each comprising: a centrally disposed portion adapted to be supported adjacent the vertical member, a lower arm portion pro-

jecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a vertical ripple fold connecting the centrally disposed portion of each unit to a centrally disposed portion of another unit.

3. An assembly having a plurality of units, each for detachably holding a rigid member at an angle projecting from a vertical support, said units being integrally formed of substantially rigid sheet material, and each comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a vertical ripple fold connecting the centrally disposed portion of each unit to a centrally disposed portion of another unit.

20 4. A unit for detachably holding a rigid member at an angle projecting from a vertical support member, said unit being integrally formed of substantially rigid sheet material and comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a member of sheet material for substantially rigidly interconnecting said units together.

25 5. A unit for detachably holding a rigid member at an angle projecting from a vertical support member, said unit being integrally formed of substantially rigid sheet material and comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a member of sheet material for substantially rigidly interconnecting said units together.

30 6. A unit for detachably holding a rigid member at an angle projecting from a vertical support member, said unit being integrally formed of substantially rigid sheet material and comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a member of sheet material for substantially rigidly interconnecting said units together.

35 7. A unit for detachably holding a rigid member at an angle projecting from a vertical support member, said unit being integrally formed of substantially rigid sheet material and comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a member of sheet material for substantially rigidly interconnecting said units together.

40 8. A unit for detachably holding a rigid member at an angle projecting from a vertical support member, said unit being integrally formed of substantially rigid sheet material and comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a member of sheet material for substantially rigidly interconnecting said units together.

45 9. A unit for detachably holding a rigid member at an angle projecting from a vertical support member, said unit being integrally formed of substantially rigid sheet material and comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a member of sheet material for substantially rigidly interconnecting said units together.

50 10. A unit for detachably holding a rigid member at an angle projecting from a vertical support member, said unit being integrally formed of substantially rigid sheet material and comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a member of sheet material for substantially rigidly interconnecting said units together.

55 11. A unit for detachably holding a rigid member at an angle projecting from a vertical support member, said unit being integrally formed of substantially rigid sheet material and comprising: a centrally disposed portion adapted to be supported adjacent the vertical member, a lower arm portion projecting outwardly and at an angle to the base of said central portion and provided with an opening therein, and an upper arm portion projecting outwardly from a position near the upper end of said central portion, said upper arm having a terminal portion disposed at the same angle to the central portion as the lower arm but being outwardly spaced a greater distance away from said central portion than the lower arm, and said terminal portion being provided with an opening in alignment with the opening in the lower arm, said units being disposed in a radial arrangement with respect to said vertical support and providing a central vertically disposed opening for accommodating said vertical support, and means for interconnecting said units together, said means including a member of sheet material for substantially rigidly interconnecting said units together.
